UNITED STATES PATENT OFFICE.

EDWD. W. STEPHENS AND RICHD. JENKINS, OF COVINGTON, KENTUCKY.

RAILROAD-RAIL.

Specification of Letters Patent No. 18,023, dated August 18, 1857.

To all whom it may concern:

Be it known that we, EDWARD W. STEPHENS and RICHARD JENKINS, both of Covington, Kenton county, Kentucky, have invented a new and useful Improvement in Rails for Railroads; and we hereby declare the following to be a full and exact description thereof, reference being had to the accompanying drawings, making part of this 10 specification.

The object of our invention is the formation of a rail of greater efficiency and less weight than any now in use.

In the accompanying drawings Figure 1 15 is a perspective view of an end of a rail formed on our plan and placed in position within the chair. Fig. 2 is an end view of the rail. Fig. 3 is a side elevation representing the form of rolls employed by us in the 20 manufacture of these rails. Fig. 4 represents a modification of our form of rail.

The greatest strain to which a rail-road rail is subjected being in directions obliquely downward and outward (compounded of 25 the weight and side-surfing forces of the train; see Fig. 4) it has become a desideratum to contrive a form of rail that with the necessary breadth of the top and bottom surfaces, should contain along its connecting portion or web a continuous substance of metal in the line of greatest strain. These requisites have been sought to be combined in the form familiarly known as the **T** rail, in which a solid continuity of 30 substance is presented in the line of greatest strain, with less metal than in any other used form.

Our improvement consists in forming a **T** rail with an aperture (*a*) extending 40 lengthwise through the thick upper portion of the rail. The tread or track (*b*) is supported on a web (*c*, *d*, *d'*) which being formed at first in two flat parts (like a **U** rail) these become in the act of rolling 45 welded together at the neck (*c*), while the two branches (*d*) (*d'*) diverging as represented, support respectively the outer and inner edges of the track. A channel (*e*) may also be formed along the middle of the 50 sole (*f*) or the rail may be rolled entire at this point. The successive stages of formation by our rolls are exhibited in Fig. 3, a portion of the inner surfaces of the web in the last "pass" becoming in the act of rolling 55 welded together as represented, so as

to form a solid neck. The represented hollowing of the upper portion of the web reduces the weight of a rail about nine pounds per lineal yard, while the permanency and efficiency of the rail are increased 60 rather than diminished because:—1stly, the substance of the rail being subjected to a very thorough rolling is so much toughened as to be comparatively exempt from bruising, scaling and lamination; 2ndly, the 65 nearly uniform thickness or substance of all parts of the rail diminishes the liability to those transverse cracks or "clinkings" across the top which now frequently occur from atmospheric changes of temperature 70 both before and after the rails leave the mill; 3rdly, a rail of hollow or tubular form being less liable to have its fibrous texture impaired with use the fatalities arising from the snapping asunder of the rail under a 75 passing train will be of much less frequent occurrence. This is evident from experiments in analogous cases, as for example a recent trial in England where a hollow and a solid axle were run without oil in a lathe 80 for two hours at a speed corresponding to twenty miles per hour traveling. The solid journal after receiving 179 blows from a hand hammer, broke off quite short and crystalline, while the hollow journal would 85 not break at all transversely but after receiving 400 blows parted longitudinally in several places with no perceptible change in the fibrous texture of the iron. From observation of the fractured surfaces of solid shafts and axles it would appear that crystallization commences centrally or near their axial line, perhaps because in the process of manufacture the central parts are 90 least drawn out. Another advantageous 95 feature of our plan consists in the facility for splicing or making a continuous rail by inserting a plug (*g*) at the joints. This answers all the purposes proposed to be effected by the various forms of what are 100 called "compound" rails while it is free from their weakening subdivisions and their objectionable weight of metal.

We are aware that it has been proposed to construct railway rails by bending the 105 sides of a **U** rail in such manner as to nearly or quite meet at the base, as in the English patent of T. A. Kinder, No. 2,730, 1853, and do not wish to be understood as claiming any devices where the sides remain un- 110

welded, an essential feature of our invention being, the formation of an entire and complete **T** rail web.

We claim as new and of our invention 5 herein:—

The tubular **T** railroad rail constructed in form and manner substantially as set forth; that is to say, having the two portions of its web welded together at the neck and

branching to the outer and inner edges respectively of the tread or track of the rail.

In testimony of which invention we hereunto set our hands.

E. W. STEPHENS.
RICH'D. JENKINS.
